UNITED STATES PATENT OFFICE.

ALBERT WARD PATTISON, OF LOCKPORT, NEW YORK.

VAPORIZER HYDROCARBON-BURNER.

1,383,015.

Specification of Letters Patent. Patented June 28, 1921.

Application filed May 25, 1920. Serial No. 384,189.

To all whom it may concern:

Be it known that I, ALBERT WARD PATTISON, a citizen of the United States, residing at Lockport, in the county of Niagara and

5 State of New York, have invented certain new and useful Improvements in Vaporizer Hydrocarbon-Burners, of which the following is a specification.

This invention relates to burners of the 10 type applicable to existing stoves, heaters, and the like, built to use solid fuel, such as coal, to convert them into stoves which can use liquid fuel, such as kerosene.

One object of the invention is to provide 15 a burner of the character specified having means for preventing formation and deposition of carbon upon the parts thereof.

Another object is to provide a burner having certain felicitous refinements of structure, going to make up the ultimate perfection of the burner in its entirety, as will appear hereinafter.

With these objects in view, the invention resides in the novel construction, combination and arrangement of parts, as will be fully hereinafter described in the specification, summed up in the claims, and illustrated in the drawings.

The accompanying drawings clearly disclose an exemplary construction capable of carrying out the underlying principles of the invention. Like reference characters denote corresponding parts throughout the several views. Briefly described:

35 Figure 1 is a view in side elevation of the burner of my invention;

Fig. 2 is a top plan view thereof;

Fig. 3 is a longitudinal sectional view on the line 3—3, Fig. 2;

40 Fig. 4 is a transverse sectional view, on the line 4—4, Fig. 2;

Fig. 5 is a top plan view of the base portion of the burner; and

Fig. 6 is a fragmentary view of a slight 45 modification;

Fig. 7 is a longitudinal sectional view taken on a line corresponding to 3—3, Fig. 2, of a modification; and

Fig. 8 is a sectional view, on line 8—8, 50 Fig. 7.

Referring, now, in detail to the drawings, and, first, to Figs. 1 to 5 thereof:

1 designates a base-plate adapted to rest upon the grate of the usual coal-or wood-burning stove, and may, as shown, be substantially rectangular in outline.

The base-plate is provided with a plurality of preferably circular openings 2, four being shown, one thereof being located at each corner of the base-plate.

60 Surrounding each opening is a vertical, tubular flange 3, provided with an interior, ring-shaped ledge 4, constituting a support for a spider-like dome-member 5 having a plurality of downwardly-curved, hollow legs 65 or tubes 6 extending from a hollow central portion 6' and resting, at their lower or free ends upon the ledges 4.

The central portion 6' has a bottom, annular opening 7, over the wall of which is spun 70 the mouth portion 8 of an inverted truncated cone-shaped screen 9, the lower edge of which is inturned to form an annular flange 10 supporting a hollow, preferably spheroidal body 11 numerously apertured, as 75 shown at 12, for a purpose presently appearing.

Tapped into the top of said body 11 is a vertically disposed branch pipe 13, communicating, by a T-union 14, with a pipe 15 80 leading from a suitable source of water supply (not shown).

Threaded into the T-union 14 and in alignment with the pipe 13 is a vertical supporting rod 16, having a threaded upper portion 85 17 passing through the top of the central hollow portion 6' and carrying nuts 18, 18 bearing against the upper and under surface of said top of the member 6'.

Disposed beneath and in vertical alignment with the spheroidal body 11 is a second hollow, preferably spheroidal body 19 supported by the upper, threaded end 20 of an oil-supply pipe 21 leading from a suitable source of fuel-supply, preferably an overhead tank or reservoir (not shown), said spheroidal body 19 being apertured, at its top, as shown at 22. Said spheroidal body 19 constitutes an oil-well.

The base-plate 1 is provided with an 100 standing annular bead 23 encircling and concentric with the spheroidal body 19, for a purpose presently appearing.

The base-plate is furthermore provided with longitudinally-extending grooves 24, 105 24 upon the upper side or face thereof, which grooves are convergently inclined, so that they meet, as shown at 25, and thence lead to an opening 26 in the base-plate, at one end thereof, into which an outlet-pipe is tapped. 110 The function of said grooves is to collect any overflow of oil escaping over the top of the

bead 23 and conduct it to said outlet-pipe tapped into the opening 26, which outlet-pipe may discharge into a suitable reservoir. The grooves 24, 24 may be of gradually decreasing depth from the point where they empty into the outlet-opening 26 to the other ends thereof, so that the oil passing into said grooves will have a gravity flow to the outlet 26.

10 In operation, the device is applied to an existing stove, such as a cook stove, by resting the base plate 1 upon the grate and then connecting the fuel-pipe 21 from an oil-tank to the base-plate. Fire-clay is then placed around the base-plate upon the grate, so that all the draft from the bottom of the stove, or ashpit, upwardly will be through the legs or tubes 6 of the spider-like dome.

Assuming, then, that the device has been installed, as above outlined, fuel oil is let into the feed-pipe 21, whence it will flow out into the well 19, and thence through the opening 22 into the shallow tray 23. A match applied to the oil in said tray will set it on fire, which heats the spheroidal body 19, and thus vaporizes the incoming oil. Flame from the burning oil rises around the legs of the spider-like dome, and they become red-hot, so that air coming from the ash-pit into them through the openings 2 is heated to a high temperature. The air passes from the legs 6 into the hollow central member 6, and thence escapes through the bottom opening 7 thereof, whereupon it passes through the screen 9 and mixes with the flame from the burning oil, insuring the necessary combustion. The products of combustion passing between the legs and over the top of the spider-like dome effectively heat the stove in which the burner is installed. The flue of the chimney and the blast of the flame cause a continuous suction of air from the ash pit up through the legs of the spider-like dome and out through the outlet 7 and thence through the screen 9 into the flame.

In operation, also, water passing from the water-supply pipe 15 through the branch pipe 13 into the spheroidal body 11, and thence through the openings 12, issues through the screen 9 in the form of steam, because of the highly-heated condition of said screen and body 11. This steam mixes with the air also passing through the screen, and with the vaporized oil issuing from the opening 22 of the spheroidal body 19, and prevents formation and deposition of carbon upon the parts of the burner.

Fig. 6 discloses a slight modification, in which, instead of the spheroidal body 11 of the device of the preceding figures, a substantially inverted cone-shaped hollow body 12' is used. With this exception, the parts of the burner of Fig. 6 are identical with those of the burner of the preceding figures.

Referring, now, in detail to Figs. 7 and 8:

The modified form of burner shown in these figures is adapted more particularly for use in burning crude or fuel oils. For this purpose, it is desirable to introduce steam into the hollow body 19' (corresponding to the element 19 of the devices of the preceding figures). To this end, a plurality of steam pipes 27 (herein shown as four in number) communicate, by means of elbows 28 tapped into the hollow member 12', with said member, and, by means of elbows 29 tapped into the body 19', with said body, which latter is provided with the outlet orifice 22' for the oil fed to said body by the pipe 21' tapped into the bottom thereof. A water-pipe 13' is tapped into the top of the member 12'.

In other respects, the structure shown in Figs. 7 and 8 is the same as that described in connection with the preceding figures of the drawings, and, therefore, a description of such parts common to all forms of my invention will not be repeated.

The operation of the burner of Figs. 7 and 8 will be apparent: The water passing through the pipe 13' into the body 12' will be there converted into steam, and will pass through the pipes 27 into the oil-receptacle 19', where it is mixed with the heavy oil 95 therein and passed out of the exit opening 22' when so mixed.

Having thus fully described my invention, what I claim as new and desire to secure by Letters-Patent is:

1. A hydrocarbon burner comprising the combination of a base provided with air-apertures, arched air-tubes communicating with said apertures and converging toward a common central portion provided with an opening in its bottom, a screen depending from said opening in the bottom of said central portion, means for projecting water through said screen, and an oil-supply pipe projecting through said base-plate and disposed beneath said screen.

2. A hydrocarbon burner comprising the combination of a base provided with air-apertures, arched air-tubes communicating with said apertures and converging toward a common central portion provided with an opening in its bottom, a screen depending from said opening in said bottom, a hollow, apertured member within said screen, means for supplying water to said member, and an oil-supply pipe projecting through said base-plate and disposed beneath said screen.

3. A hydrocarbon burner comprising the combination of a base provided with air-apertures, arched air-tubes communicating with said apertures and converging toward a common central portion provided with a bottom opening, a screen depending from said bottom opening, a hollow, spheroidal member within said screen, means for sup-

plying water to said member, and an oil-supply pipe projecting through said base-plate and disposed beneath said screen.

4. A hydrocarbon burner comprising the combination of a base provided with air-apertures, arched air-tubes communicating with said apertures and converging toward a common central portion provided with a bottom opening, a screen depending from 10 said bottom opening and provided with a lower marginal, inturned, annular flange, a hollow, apertured, spheroidal member disposed within said screen and supported upon said flange, means for supplying water to 15 said member, and an oil-supply pipe projecting through said base-plate and disposed beneath said screen.
5. A hydrocarbon burner comprising the combination of a base provided with air-apertures, arched air-tubes communicating 20 with said apertures and converging toward a common central portion having a bottom opening, a screen depending from said bottom opening, an oil-supply pipe projecting through said base-plate and disposed beneath said screen, and a hollow, apertured body supported upon the end of said pipe 25 projecting above said base.
6. A hydrocarbon burner comprising the combination of a base provided with air-apertures, arched air-tubes communicating 30 with said apertures and converging toward a common central portion having a bottom

opening, a screen depending from said bottom opening, means for projecting water through said screen, an oil-supply pipe projecting through said base and disposed beneath said screen, and a hollow, apertured, spheroidal body supported upon the end of 40 said pipe projecting above said base.

7. A hydrocarbon burner comprising the combination of a base provided with air-apertures, arched air-tubes communicating with said apertures and converging toward 45 a common central portion having a bottom opening, a screen depending from said bottom opening, a hollow, apertured body supported by said screen, means for supplying water to said body, an oil-supply pipe projecting through said base and disposed beneath said screen, and a hollow, apertured body supported upon the end of said pipe 50 projecting above said base.

8. A hydrocarbon burner including a base-plate provided with air-apertures and with upward-projecting, tubular portions surrounding said air-apertures, said portions having interior ledges, arched air-tubes converging toward a common central portion 60 having a bottom opening, the lower ends of the air-tubes being supported upon said ledges, a water-pipe projecting through said bottom opening, and an oil-feed pipe projecting through said base-plate and disposed 65 beneath said water-pipe.

In testimony whereof, I affix my signature.
ALBERT WARD PATTISON.
